(57) **CLAIM**

The ornamental design for a firearm sight accessory mount, as shown and described.

DESCRIPTION

FIG. 1 is a perspective view from the behind, above, and the right side of a first embodiment of a firearm sight accessory mount;

FIG. 2 is a right side elevational view thereof;

FIG. 3 is a left side elevational view thereof;

FIG. 4 is a rear elevational thereof;

FIG. 5 is a front side elevational view thereof;

FIG. 6 is a top plan view thereof; and

FIG. 7 is a bottom plan view thereof;

FIG. 8 is a perspective view from the behind, above, and the right side of a second embodiment thereof;

FIG. 9 is a right side elevational view thereof;

FIG. 10 is a left side elevational view thereof;

FIG. 11 is a rear elevational view thereof;

FIG. 12 is a front elevational view thereof;

FIG. 13 is a top plan view thereof; and,

FIG. 14 is a bottom plan view thereof.

The uniformly broken lines shown in the drawings represent portions of the firearm sight accessory mount that form no part of the claimed design.

1 Claim, 14 Drawing Sheets
